UNITED STATES PATENT OFFICE.

HENRY G. O'BRIEN, OF WARREN, OHIO, ASSIGNOR TO THE TRUMBULL STEEL COMPANY, OF WARREN, OHIO, A CORPORATION OF OHIO.

CONTINUOUS HOT MILL.

1,425,537.

Specification of Letters Patent. Patented Aug. 15, 1922.

Application filed September 4, 1919. Serial No. 321,660.

To all whom it may concern:

Be it known that I, HENRY G. O'BRIEN, residing at Warren, in the county of Trumbull and State of Ohio, a citizen of the

5 United States, have invented or discovered certain new and useful Improvements in Continuous Hot Mills, of which improvements the following is a specification.

My invention relates to improvements in 10 hot mills for rolling metal, and is particularly advantageous in strip mills; the object is to render the mill more "flexible"—capable, that is to say, of producing strips of wider range, in the matter of thickness 15 particularly, than otherwise can be got from a single mill installation, and this with greatest economy of speed, power, and floor space.

Understanding of the invention will be 20 aided by reference to the accompanying sheet of drawings which shows diagrammatically and in plan a mill installation such as may embody my invention.

The mill so diagrammatically shown (a 25 strip mill—though in this particular respect my invention is not limited—it might be a bar mill or a rod mill) consists of thirteen roll stands, indicated by the successive numerals 1 to 13. Of these the first seven roll 30 stands constitute, in mill parlance, the "roughing rolls" or the "roughing mill" (using the word mill in a more particular sense than when applied to the entire assembly), and the last four constitute the "finishing rolls" or "finishing mill." The two intermediate roll stands, 8 and 9, stand apart, as will presently appear, in respect to the mode of driving, but such segregation of 35 these two stands is not essential to my invention in its broader aspects.

Heretofore the successive rolls of continuous mills have ordinarily been driven from a common motor; in some instances the roughing rolls and the finishing rolls have 45 been grouped, each group apart, and each driven as a group from one motor; it has even been proposed to drive each separate roll stand of a continuous mill by a motor of its own. But never heretofore, so far as 50 I know, has it been proposed to drive a continuous mill as I drive it.—and herein is the fundamental characteristic of my invention: I group the several stands of roughing rolls together and drive the group by one 55 motor; or perhaps, and as the drawings show, I group these stands of roughing rolls

in a plurality of groups and drive each group by a single motor; and then, respecting the stands of finishing rolls, I drive each roll stand by a separate motor.

By such an arrangement I have the economies of the group arrangement where it is altogether advantageous,—at the roughing end, namely, of the mill; and I have the advantage of separate drive, where separate drive is advantageous, that is, at the finishing end of the mill. Separate drive of the several roll stands of the finishing rolls is advantageous, in that the mill is made "flexible" in adaptability to a product of varying 70 gauge.

Referring to the drawing, a succession of roll stands 1 to 13 is shown, on the line of rolling A—B, the direction of the advance of the material under operation being indicated by the arrow *a*. The group of roll stands 1 to 7 inclusive at the roughing end of the mill is driven by a single motor 14; a second and intermediate group, consisting of the two horizontal roll stands 8 and 9 (which may be termed "roughing rolls" or "intermediate rolls"), may be driven by a single motor 15; while the four roll stands 10-13 inclusive at the finishing end of the mill are driven, each by a separate motor, 80 16-19 inclusive.

As indicated in the drawing, stands 2, 3, 5, and 6 of the roughing mill are stands of horizontally placed rolls, for flat rolling, while stands 1, 4 and 7 are "edging" passes. 90 The rolls of these edging passes may if desired be driven by means other than motor 14.

It should be remarked too that the motors 16-19 (and motors 14 and 15 also, if desired) 95 are conveniently variable-speed motors.

Confining attention next to the roll stands at the finishing end of the mill, and to their more minute construction, I find it advantageous—and this feature, though not in itself alone a part of my present invention, is, when combined with the roll-driving arrangement already described, a consequent advantage (for in such combination the "flexibility" of the mill, already alluded to 100 is greatly enhanced)—I find it advantageous to constitute the final roll stand 13, and preferably the next to last stand 12 also a "friction" roll pass; a roll pass, that is to say, in which one of the pair of rolls and only one 105 is positively driven, the companion roll turning by friction as work progresses be-

tween the two rolls. And, further, I preferably superadd to such friction-roll pass or roll passes the invention of United States Letters Patent, No. 1,336,177, granted to 5 Joseph Withers and myself, April 6th, 1920,—the invention, namely, of positively driving the idle member of the roll pair, in case its rate of turning under the normal impulse by friction is arrested or falls below a certain predetermined speed.

Finally, and herein lies a further consequent advantage of my invention, I make the final roll stand, or the rolls thereof, and if preferred other stands of finishing rolls 15 or the rolls thereof, removable and replaceable.

Heretofore sheet or strips of a certain thickness requiring certain limitation in roll dimensions, have imposed corresponding 20 limitations on any given mill, and no mill could produce sheets or strips of thickness other than its rolls, because of their dimensions, were adapted to produce. If, for example, it be a strip one eighth of an inch in 25 thickness which is to be rolled, the "friction" roll (that is to say, or linearly, the upper roll) of each finishing roll-pass must be a twelve-inch roll; but, if strip of finer gauge be required, twelve-inch rolls will be inadequate to produce it. There is need for rolls 30 of smaller diameter (ten-inch rolls, say) in the use of which the pressure in the roll pass upon the metal under operation will be concentrated within a smaller area; further, 35 twelve-inch rolls are ordinarily made of such length of barrel that the "give" or springiness will render the rolling of finer gauges uncertain and inaccurate. The rolling of strip of gauges finer than one eighth of an inch has heretofore required a separate 40 and distinct mill, for those gauges only; or, as has been more commonly the case, the finer gauges have been produced by subsequent cold-rolling of the previously rolled

one-eighth material—and that, of course, has been accomplished at appreciably increased cost.

Now, by providing separate motors for the several passes of finishing rolls, and particularly by providing variable speed 50 motors for driving the rolls of the several passes, new possibilities open; I can then make my several roll passes removable and replaceable, and, adopting alternate roll passes of rolls of different sizes (of such 55 different sizes, for example, as above suggested) I can render my improved mill "flexible" as no other mill known to me is flexible, and can in one and the same mill, with the adaptations described, roll material 60 of wider range in dimension than has hitherto been achieved.

Thus in selecting and combining these several features of mill construction I attain not merely the several benefits known to be 65 attributable to them, but, more than that, I attain a mill of economies and capacities never before attained, within my knowledge.

It will be understood that my invention is not limited to details of number and arrangement, but is broadly attained in the arrangement herein claimed.

I claim as my invention:

A hot mill for rolling metal including a plurality of roughing-roll stands and a plurality of finishing-roll stands, a common motor driving the rolls of the several roughing-roll stands, a plurality of motors corresponding in number with the finishing-roll stands and connected operatively, one 80 to each of said finishing-roll stands.

In testimony whereof I have hereunto set my hand.

HENRY G. O'BRIEN
